BAROMETRIC REGULATOR

Morris W. Crew, Shaker Heights, Ohio, assignor
to The Hotstream Heater Company, Cleveland,
Ohio, a corporation of Ohio

Application April 19, 1941, Serial No. 389,304

2 Claims. (Cl. 236—45)

This invention relates to improvements in barometric regulators or dampers which are balanced against the effect of a draft tending to open them.

An object of the present invention is to provide a damper construction wherein a counterweight is movable across the face of the damper to vary the balanced effect thereof, together with motor means for moving the counterweight, this motor means being mounted directly upon the damper.

Another object of the present invention is to provide the combination of a damper mounted for pivotal movement about an off-center axis whereby a greater weight of the damper is on one side of the axis than on the other, together with a shiftable counterweight and a motor for moving the counterweight which is mounted on the lighter side of the damper so as to at least partially counterbalance the heavier side of the damper.

Other objects and advantages of the invention reside in the construction and arrangement of the parts so as to carry out the desired functions and the essential features thereof will be set forth in the claims.

In the drawing, Fig. 1 is an elevational view of a damper equipped with my improved mechanism; Fig. 2 is a sectional view of the same taken along the line 2—2 of Fig. 1; while Fig. 3 is a wiring diagram showing one manner in which the equipment may be used.

In the drawing, a flue is indicated at 10 having an open end at 11 and the other end of which 12 may be connected to the breeching leading to a stack or the like so that stack draft is effective on the right-hand face of the damper as shown in Fig. 2 and atmospheric pressure is effective upon the left-hand face thereof. A shaft 13 extends across the damper and is connected to the main plate 14 of the damper. The ends of shaft 13 are mounted in suitable bearings 15 which are carried by the flue walls. Stiffener angles 16 extend vertically along the damper plate to stiffen it and a channel 17 extends horizontally across the damper for stiffening purposes. It will be noted that the pivot shaft 13 is located off-center with respect to the damper and in fact is about one-third of the depth of the flue from the top or two-thirds up from the bottom. It results from this construction that without the use of counterweights the weight of the damper below the shaft 13 would tend always to return the damper to the closed position shown in Fig. 2. The effect of draft in the breeching connected at the point 12 is to cause the damper to swing in a

counterclockwise direction about the shaft 13 as viewed in Fig. 2 upon an increase in the draft or suction.

Means is provided to vary the balance of the damper about the shaft 13 so as to cause the damper to open with higher or lower draft as desired. The means here shown comprises a counterweight 18 having threaded engagement with a screw 19, which is mounted parallel to and adjacent the damper plate 14. The mounting comprises a bracket 20 holding the bearing for the lower end of screw 19 and a bracket 21 which holds a bearing for the upper end of the screw. The counterweight is provided with one or more rollers 22 which ride upon the right-hand face of damper plate 14 as viewed in Fig. 2 and prevent rotation of the counterweight relative to the screw. Thus rotation of the screw will cause movement of the counterweight crosswise of the damper so as to vary the position of counterweight 18 with respect to the pivotal axis 13. This changes the balance of the damper about the shaft 13.

Power means is provided for moving the counterweight. The means here shown comprises a motor 23 mounted on the damper plate 14 and driving through reduction gearing 24 an output shaft 25 which is pinned or otherwise connected to the screw 19. An upper bearing 26 may be provided for the output shaft 25 if desired or the bearings in the motor and reduction unit may be relied upon to support the upper end of screw 19. Obviously rotation of motor 23 in one direction will cause travel of counterweight 18 downwardly along the screw 19 and reverse movement of motor 23 will cause upward movement of counterweight 18.

Limit switches 27 and 28 are provided for stopping movement of the motor if the counterweight 18 reaches the end of its travel in either direction. These switches may be of the type disclosed in Patent No. 1,960,020, granted May 22, 1934, to P. K. McGall. For instance if counterweight 18 moves upward slightly from the position shown in Fig. 2 it will strike the blade 27a of switch 27 and open the motor driving circuit which causes weight 18 to move upwardly. When weight 18 reaches the lower limit of its travel it will strike collar 29 which is pinned to shaft 30 and normally urged upwardly by spring 31. Pinned to the upper end of rod 30 is another collar 32 which when pulled downwardly will engage blade 28a of switch 28 and open that circuit of motor 23 which drives weight 18 downwardly. The wiring connections to motor 23

and switches 27 and 28 are shown diagrammatically in Fig. 3 but are not indicated in Figs. 1 and 2. However a conduit 33 is provided by means of which the wires may be led from the motor and the switches into the hollow space beneath channel 17 and thus off to one side of the damper where they may be connected to a suitable source of electricity.

Referring to the diagram of Fig. 3, line 34 leads from one side of the electric supply line through a manual control or from that side of an automatic controller tending to increase the draft, whereas line 35 leads from another side of the line connected with a source of electricity through a manual control or an automatic controller which tends to decrease the amount of draft. Line 36 is the common return line in either case.

It is believed that the operation of my improved regulator will now be readily understood. Assuming the limit switches 27 and 28 are closed, if the side of the line indicated at 34 is closed by means of a manual button or an automatic controller, motor 23 will be energized and will rotate screw 19 so as to carry counterweight 18 downwardly. This increases the tendency of the damper to remain closed and greater draft will be necessary in the breeching connected at 12 before the damper can be opened. If on the other hand a manual button or an automatic controller closes the circuit through lines 35 and 36, motor 23 will be operated in the opposite direction and will cause weight 18 to rise so that the damper opens more easily and there will be less draft in the breeching.

It will be noted that a metallic cover 37 has been provided over motor 23 and switches 27 and 28 to protect them. Also a cover 38 on the opposite side of the damper serves to protect the screw 19 and all parts associated with it there.

What I claim is:

1. In combination, a draft damper having a pivotal mounting in a flue, said mounting providing a pivotal axis off center relative to the damper so that there is less of the weight of the damper on one side of said axis than on the other side, a screw close to said damper and parallel to its face, a counterweight threaded on said screw for movement therealong by rotation of said screw, a motor having a driving connection with said screw for rotating the latter, said motor being mounted on said damper close to the face thereof and on that side of said axis where less weight of said damper is disposed, said motor being located near one end of said screw, two limit switches mounted near said motor, one of said switches being operable by said counterweight at said one end of said screw, and an operator for the other of said switches extending to the other end of said screw and there engageable by said counterweight.
2. In combination in a furnace flue having a stack connection and a cold air connection, a draft damper having a pivotal mounting in said flue between said connections, said mounting providing a pivotal axis off center relative to the damper so that there is less of the weight of the damper on one side of said axis than on the other side, a counterweight mounted for movement across said damper at an angle to said axis, and a motor having a driving connection with said counterweight for moving it, said motor being mounted on said damper within the area of said damper and on that side of said axis where less weight of the damper is disposed, whereby said motor counterbalances at least part of the heavier side of the damper, and said motor being mounted on said damper on the side thereof toward said cold air connection so that said motor is cooled by the flow of air into said flue.

MORRIS W. CREW.
